CLAIM

The ornamental design for a cooktop for portable apparatus, as shown and described.

DESCRIPTION

FIG. 1 is a top perspective view of a cooktop for portable apparatus showing my new design;

FIG. 2 is a bottom perspective view thereof;

FIG. 3 is a top view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is a bottom view thereof.

The broken lines in the drawings illustrate portions of the cooktop for portable apparatus that form no part of the claimed design.
